AUTOMOBILE DOOR DOVETAIL

David W. Dougherty, Wayville, Adelaide, South Australia, Australia

Application June 17, 1937, Serial No. 148,708

2 Claims. (Cl. 16—85)

This invention presents an automobile door dovetail.

In automobile doors and the like it is necessary to wedge the door tightly when locked in order to relieve the hinges of strain and to prevent relative movement which would cause rattling and wear. The main object of my invention therefore is to provide a lock strike plate and a spring set dovetail so that as the door is closed and locked the dovetail wedges the door tightly and absolutely prevents all looseness and rattling.

Another object is to provide an assembly of this kind in which the strike plate or block is rigidly mounted but the dovetail has one portion secured to the door and the other portion slidably associated with the strike block and spring set so as to afford a resiliency as the two portions wedge together which will effect a constant spring action on the dovetail and will compensate for any wear entailed by repeated locking and unlocking of the door.

Another object is to provide an assembly of this kind in a simple, durable, practical and inexpensive form.

With these and other objects in view the invention resides in the novel construction and arrangement of parts as hereinafter fully set forth and claimed, reference being had to the accompanying drawing as showing a preferred embodiment of my invention for purposes of exemplification.

In the drawing:

Figure 1 is an inside elevation of a door jamb showing the strike block and resiliently mounted dovetail plate.

Figure 2 is an edge view of the door showing the latch and the fixed dovetail plate or wedge.

Figure 3 is a cross section along the line 3—3 showing however both the door jamb and the door in the locked position of the parts.

Figure 4 is a composite side and edge view of the resiliently mounted dovetail plate.

Figure 5 is a detail perspective view of the spring retainer plate alone.

Referring now with more particularity to the drawing the reference character A designates the door jamb having in its edge a recess B to receive the parts of my resilient dovetail mounting and C designates the door having the usual lock D mounted in its edge.

In accordance with my invention a fixed wedge or dovetail plate 6 is secured by screws 7 to the door edge C immediately behind the lock bolt E, that is, behind the bolt in the direction in

which the door moves in closing. Flanges 8 are turned outwardly from the upper and lower margins of the plate 6 and converge forwardly or toward the bolt E by reason of the wedge shape of the plate. The frontal or entering ends of these flanges 8 are turned or curved arcuately inward as shown at 9.

The lock strike assembly 10 comprises a mounting plate 11 secured over the jamb recess B by screws 12 and the strike block 13 is rigidly affixed to this plate 10 by rivets 14. This block 13 has steps 15 which slope toward the plate 10 in the direction of the outer side of the jamb A and so that the rounded face of the lock bolt E will ride over these steps as the door closes 15 and finally the bolt will spring out behind the inner end 16 of the block as shown to lock the door.

The strike block 13 is recessed out as at 17 next the plate 11 between the rivets 14 and the plate 20 11 has a slot 18 cut adjacent the outer end of this recess.

A resiliently mounted dovetail plate or receptacle plate 19 is provided and same is, like the plate 6, wedge shaped and has the converging 25 wedge flanges 20 turned arcuately inward at their narrowest ends as at 21. This plate 19 is cut away or notched out at 22 medially at both its inner and outer ends to provide a narrow connecting web or strip 23 which will fit within the 30 recess 17 in the strike block 13 which thus confines the strip 23 and holds the plate 19 on the mounting plate 11 as shown. The strip 23 however is narrower than the length of the recess 17 and thus the dovetail plate 19 is allowed limited sliding motion over the mounting plate 11 35 in a direction parallel to the length of the strike block 13. Guide ears 24 are turned outward from the lateral ends of the notches 22 and slidably engage the lateral margins of the strike block 40 13 while a spring lug 25 is turned from the outermost notch 22 inward through the slot 18 in the mounting plate 11 into the jamb recess B.

A rectangular box-like spring housing 26 is mounted by its flanges 27 beneath the rivets 14 45 and is disposed in the aforesaid recess B. A plurality of expansion coil springs 28 are placed side by side in this housing 26 and braced between the lug 25 and the innermost end of the housing 26 and exert an outward pressure on the lug 25. 50 A spring retainer plate 29 is provided and same has one end 30 turned so as to fall behind the inner ends of the springs 28 while its other end 31 is oppositely turned to fit into and against the inner edge of the slot 18 in the plate 11. 55

This plate 29 has spaced valleys or grooves 32 along its length which receive the springs 28 and hold them in alignment. The space between the plate 29 and the adjacent face of the mounting plate 11 may be packed with oil soaked felt 33 which will keep the parts within the housing 26 lubricated at all times.

Now as the door C is closed against the jamb A the flanges 8 of the fixed dovetail plate 6 will enter between the wider ends of the flanges 20 on the resiliently mounted plate 19 but before the door is fully closed these flanges will wedge together and further movement to the closed position will cause the plate 19 to be carried 15 along inwardly compressing the springs 28. Thus the desirable wedging action to prevent looseness of the door is provided and since the dovetail is resiliently mounted all wear is compensated for.

It is of course understood that my invention 20 may be applied as well to any other forms of doors where such a device is needed.

While I have herein set forth a certain preferred embodiment of my invention, it is understood that I may vary from the same in minor 25 structural details so as best to provide a practical device for the purposes intended, not departing from the spirit of the invention and within the scope of the appended claims.

I claim:

30 1. In a device of the kind described for mounting upon a door hinged vertically at one side to close horizontally upon a jamb at the opposite side, a fixed dovetail plate on the door having flanges turned outwardly from the upper and 35 lower margins of the plate and converging towards the inner side of the door, a mounting plate secured over a recess in the jamb, this plate having a vertically elongated slot adjacent its outer end and opening into the recess in the 40 jamb, a block rigidly mounted on the mounting plate, this block having at its inner face next the mounting plate a flat recess opening out at top and bottom and communicating at its outer side with the slot of the mounting plate, a movable dovetail plate having a narrowed central 45

portion and being mounted thereby thru the recess in the block, this plate having out-turned flanges at its upper and lower margins converging towards one side complementally to and in alignment with the flanges of the fixed dovetail 5 of the door, this movable plate having also a spring lug turned from the outer margin of its narrowed portion thru the slot of the mounting plate into the recess in the door jamb and having a pair of guide ears turned outward from the 10 plate for slidable engagement with the sides of the block, and expansion springs mounted within the recess in the jamb and braced between the spring lug of the movable dovetail plate and the opposite end of the jamb, whereby the movable 15 dovetail is pressed resiliently outward, the slot of the mounting plate and the recess of the block being wide enough to permit limited horizontal movement of the movable dovetail.

2. In a device of the kind described for mounting upon a hinged door closing to a jamb, a fixed dovetail plate on the door having flanges turned out at opposite margins and converging towards the inner side of the door, a mounting plate secured over a recess in the door jamb this plate being slotted at its outer side with the slot opening 20 into the said recess, a block on the mounting plate the block being recessed at its inner face next the mounting plate, this recess opening out at top and bottom and overlying at one end the 30 said slot of the mounting plate, a movable dovetail plate complementary to the fixed dovetail plate of the door, the movable plate having a narrowed central portion slidably passed thru the recess in the block and a spring lug turned from the outer 35 margin of the narrowed portion thru the slot of the mounting plate into the recess of the door jamb; ears extended from the movable plate in slidable engagement with the upper and lower sides of the block, and expansion springs mounted 40 within the recess in the door jamb and braced against the said spring lug of the movable dovetail plate to press the same resiliently outward.
